(57) **CLAIM**

The ornamental design for a display screen with graphical user interface, as shown and described.

DESCRIPTION

The FIGURE is a front view of a display screen with graphical user interface showing our new design.

The broken line showing of the display screen, text and portions of the graphical user interface form no part of the claimed design. The dash-dot line represents the boundary of the claimed design and forms no part of the claimed design.

1 Claim, 1 Drawing Sheet
